FREQUENCY BAND AND CHANNEL
SELECTING MECHANISMJacob Yavitch, Glenolden, Pa., assignor to Radio
Corporation of America, a corporation of Dela-
ware

Application December 29, 1948, Serial No. 68,025

18 Claims. (Cl. 74—10.1)

1

This invention relates to a new and useful channel and band selector mechanism which is particularly adapted for the selective control of radio apparatus, although not specifically limited thereto.

An object of this invention is to provide a novel selector mechanism wherein a single control member simultaneously moves a plurality of selective switches.

Another object of this invention is to provide a control device for operating a group of switches from a single control member, one group of switches being that of a band switch which also is coupled to vary an antenna switch and another group being that of a channel switch. The band switch selector mechanism is provided with an adjustable cam mechanism and the channel switch is provided with two switches for selectively placing in circuit a predetermined group of capacitors or other tuning elements.

Still another object of this invention is to provide an improved selective mechanism having a variable rotatable cam which permits change in a setting for different bands and which simultaneously operates an antenna tuning switch.

A feature of this invention is the arrangement of three different control units for selective switching. All the control units are simultaneously selected by the movement of a single control knob.

This invention will be more clearly understood by referring to the accompanying drawing wherein:

Fig. 1 is a plan view of the selector mechanism of this invention;

Fig. 2 is a front elevation, partly in section, of Fig. 1;

Fig. 3 is a rear elevation;

Fig. 4 is a diagrammatic showing of the gear train for the channel selector mechanism;

Fig. 5 is a diagrammatic showing of the band selector mechanism; and

Fig. 6 is an electrical circuit diagram of the channel and band switching circuit including the antenna selective switch.

Referring now in detail to Figs. 1, 2, and 4 of the drawing, an operating knob 1 is secured to a shaft 2 which shaft is journaled for rotation in a front support casting 124. A spur gear 58 is fastened for rotation on shaft 2 and meshes with another spur gear 56. Also secured to shaft 2 is a stop pin 84, the purpose of which will be explained in more detail later. The ratio between spur gears 58 and 56 being that of 11:10 which permits the knob 1 to rotate 396° for one complete cycle of

rotation, that is, from one channel position to the next, and the gear 56 to rotate 360° for one rotation of the knob 1. The gear 56 is fastened to rotate with a main operating shaft 3. Also journaled for rotation in a front support casting 124, is the main operating shaft 3 which rotates in the rear support casting 126. The front and rear support castings are spaced in operative position by four groups of spacers 13 and 14 which are secured by means of screws 15. A small pinion gear 80 is mounted for rotation with shaft 3 and is secured to shaft 3 by a pin 16 in a shoulder portion located adjacent the rear support casting 126. A large spur gear 74 meshes with pinion gear 80, which large gear 74 is mounted upon an intermediate shaft 4, the shaft 4 being journaled for rotation by a suitable bearing in the rear support casting 126. A pinion gear 76 is also secured to the intermediate shaft 4. Another large spur gear 78 is secured to an adjustable cam shaft 5. The shaft 5 is supported for rotation by needle or roller type of bearings located in both the front and rear support castings. Arranged to rotate with spur gear 78 is an adjustable cam drum 92, details of which will be described later. A control knob stop cam 72 is integral with drum 92 and rotates therewith upon movement of shaft 5. The contour of cam 72 is such as to permit nine complete cycles of rotation of knob 1 and then lock the knob 1 against further rotation in the same direction. A bell crank 86 is pivoted on casting 124 by a pin 6, the short arm of bell crank serving as a cam follower for cam 72. The long arm of bell crank 86 is provided with a depending portion 7, which engages the upper portion of a stop member shown as a lever 84 arranged on the shaft 2. As mentioned above, the knob shaft 2 is provided with a spur gear 58 which meshes with another spur gear 56 on the main operating shaft 3, and the stop lever 84 might optionally be on the form of a pin located on the spur gear 58. The shaft 5 extends slightly beyond the rear support casting and is provided with a pinion 68. The pinion 68 meshes with a gear rack 70. The rack 70 forms part of a sliding arm 102 which is provided with a similar gear rack 64 which meshes with a pinion 62 mounted for rotation on the rear support casting 126 by a shaft 8. The rear extensions of shafts 5 and 8 are provided with channel selector switch operating cranks 118 and 141 respectively.

The foregoing description is directed primarily to the channel switching mechanism. The band switching mechanism which operates in conjunc-

tion with the channel selecting mechanism will now be described in detail by reference to Figs. 1, 2, 3, and 5.

The adjustable cam drum 92 has located thereon, ten adjusting screws 96, which are secured in position 30° apart by means of a slotted retaining clamp ring 128 located within drum 92. The jacks 96 are slotted at 96a to engage the slots in clamp ring 128. Each one of the adjustable jacks 96 are provided with adjustable bushings 130, 10 which bushings are mounted for radial movement on the adjusting screws 96 and are prevented from rotation by means of pins 132 secured in drum 92 which engage a slot 134 in the bushings 130. A forked bell crank member 20 is pivoted at 21, the pivot 21 being secured to the front support casting by means of an extension arm 22. A band setting lever 23 is linked to crank 20 by means of a pin 24. The lever 23 extends away from the adjustable cam 92 and is provided with depending portion 23a having a slot 25 and a gear rack 26, the rack 26 meshing with a pinion gear 27 which pinion gear is mounted for rotation in both the front and rear support castings on a shaft 28. The band setting lever 23 is always urged in a position such as to rest upon a bushing 130 by means of a helical tension spring 98 and is stopped only by the height of the preset bushing. The spring 98 is secured at one end to extension 22 and at the other end to an adjustable stud member 29, which stud adjusts the tension on spring 98 by means of a threaded thumb nut 30. Located above and beyond rack 26 there is provided in depending portions 23a, an aperture 31, in which a stud member 32 slides. The forward end of stud 32 has mounted thereon a detent roller 34, which roller engages an approximate heart-shaped detent cam 35. Tension on roller 34 is provided by a helical compression spring 36 surrounding stud 32. The tension of spring 36 is varied by means of a bolt 37 which is threaded in bushing 38. A pin shaft 39 retains lever 23 in operative position by passing through slot 25 in the depending portion 23a. Shaft 39 is secured for rotation on ball bearings 139 located in the forked portion of the front casting 124. The forked portion of casting 124 is recessed to provide the proper support for ball bearings 139. The pinion shaft 28 extends beyond the rear support casting 126 and has secured thereto a spur gear 116 which meshes with a similar gear 114 mounted for rotation on the rear support casting. The gear 114 is an idler gear to make gears 112 and 116 rotate in the same direction. The other spur gear 112 meshes with a pinion gear 110 which is mounted on a shaft 110a for rotation on rear support casting 126 and meshes with a quadrant gear 108. The quadrant gear 108 is provided with a rotatable shaft 12 which operates an antenna selective switch 82. The gears 112 and 116 each have secured thereto a band switch coupling lever 120 and 122 respectively. An index scale 100 is marked on casting 126 and a pointer 102a is marked on gear 116 to indicate the proper setting height of bushings 130.

In the operation of this switch, when the operator moves the knob 1 and operating shaft 2 from channel position 1 to position 2, for example, the shaft 2 will complete one cycle or 396° for a 30° movement of the spacing between adjacent channel switch contacts and the spacing between the corresponding selective bushings, band and antenna switch contacts. This greater angular movement between the operating shaft 2 and the movement of the switch shafts is be-

cause of a gear ratio of 1 to 3 between the gears 80 and 74 and a ratio of 1 to 4 between gears 76 and 78 thus making a total increased gear ratio of 1 to 12 from shaft 3 to that of shaft 5. As there are only ten channel positions on drum 92 there is a total of 270° of active movement for the switch selective bushings on cam 92. This movement corresponds with a total of nine complete revolutions of shaft 3 and a corresponding active portion of the adjustable bushings of the band switch. The control knob 1 is permitted to rotate only a total amount of nine successive rotations or cycles of movement in any direction, that is, control selections are made from channel position 1 in succession up to channel position 10 and then back to 1. The above channel or dial positions, namely from 1 to 10 inclusive are not shown on the drawing but may be indicated on any suitable index plate such as, for example, an engraved dial placed in front of the panel. The stop cam 72 in cooperation with the bell crank 86 and stop pin 84 prevents more than nine successive complete rotations of the control knob 1 and also prevents the operator from going directly from position 10 to position 1 without going back through the dial or channel positions 9, 8, 7, etc. The gearing arrangement for the channel switch between control knob 1 and the shaft 5 is such that a 1.1 revolution of the control knob will move the channel switch between operating cranks 118 and 141 30° or to the next channel position. When the operator changes the channel switch position, the band switch will move from a homing position to any selective switch position from 4 to 1 depending upon the height of the preset bushings 130. For making up the difference between the increased amount of angular movement of knob 1 and that of the main operating shaft 3 the gears 58 and 56 have a ratio of 11 to 10 which will permit a greater movement for the operating knob than that of the main operating shaft 3. With this gearing arrangement it is possible to evenly divide the index on the dial into ten equal parts for the knob movement of the nine cycles of revolutions. In other words the front operating panel dial can be divided into 36° equal divisions to indicate an equivalent 30° movement between the centers of the switch contacts so that one cycle of revolution of the control knob 1 will move the contact arm of the channel switch A, 30° or to the next channel, thus any of the ten channel positions may be selected in succession up to ten and back to one. During the above mentioned movements of shafts 2, 3, and 5, the heart-shaped detent cam 35 also makes one complete revolution, and the roller 34 is moved backward by the maximum height of the cam. The band setting lever 23 is carried by the rack 26 to a homing position, and at this time the helical compression spring 36 is expanded, and the cam continues its rotation. At the time when the pointer on knob 1 approaches the next channel position, for example, channel 2, the roller 34 will be driven into the low point of the cam 35 by action of spring 36 thus permitting the tension on spring 98 to be released and drive the lever 23 so that the bell crank 20 will rest upon the next adjacent bushing 130. The height of the bushing will determine how far the bell crank 20 is permitted to drop and this height likewise determines the amount of movement for the band switch shaft by the relative relationship between the pinion gear 21 and the position of rack 26, for example, if as shown in Fig. 2 of the drawing, the bushing height is low, the band switch will be

such as to select band 1. It is possible, of course, with a device in this invention to skip from band 1 to band 4 making a total movement of 120° for the band switch at a time when the channel switch moves only 30° and again it is possible to move from position 1 to position 3 or if desired to position 2. In another arrangement, depending upon the setting of the bushings it is possible to move from position 3 to position 2 or any combination of selections depending upon the height of the bushings.

When the panel control knob 1 nears the end of its rotation it is held by the detent action of cam 35 roller 34 and spring 36. The switch arm of the band switch B is released when knob 1 is held by the detent action and is forced back by spring 98 to any of the bands 1, 2, 3, or 4 depending upon the predetermined setting of the cam bushings. The arm 23 is pulled back to the homing position by spring 98 beyond band 4. Upon release of knob 1 movement of arm 23 is stopped by the preset height of the bushings or jacks 130 to the respective positions 2, 3, etc. Any band may be selected by setting the height of the bushing 130 above the periphery of the metal drum 92. The height of the bushing determines how far the arm 23 can move the band switch through the rack and pinion arrangement or to rotate switch arms 120 and 122 from the homing or (X) position. Thus by having a band setting bushing for each channel position, any band coil and antenna coil tap may be selected for any one of the channel trimmer or tuning capacitor settings.

In one arrangement of the selector mechanism of this invention which was used with a transmitter-receiver having a frequency range in the order of 1.5 megacycles to 12 megacycles and a selective arrangement of four bands. For example, the first band can be arranged to cover a frequency range from 1.5 to 3 megacycles, the second band to cover a frequency range from 3 to 6 megacycles, the third band can cover a frequency range from 6 to 9 megacycles, and the fourth band can cover a range from 9 to 12 megacycles. As mentioned above there is also provided with a band switch the position X wherein the band switch is driven to the homing position by the detent cam 35 roller 34 and the spring loading of spring 36. Coupled with the band switch gears is the antenna switch ANT and shaft 12 operated to move simultaneously therewith.

Referring to the circuit diagram Fig. 6, one example of the use of the switch selecting mechanism of this invention is explained in connection with such a transceiver having four bands wherein the channel switch is divided in two parts comprising switches A and A1. The two sets of switches are provided to make the set more compact. If desired only a single shaft and one switch may be used. The switches comprise a plurality of wafers like that shown as antenna switch 82 in Fig. 3, except that ten contacts are provided. The band switch is also divided in two parts and comprises switches B and B1. Also coupled with the band switches is an antenna switch ANT indicated as 82 in Fig. 3. Associated with the channel switch contacts are trimmer capacitors 1C to 10C inclusive. The band switch has associated therewith, four inductive elements which are connected to the respective contacts of switches B and B1. A series capacitor and inductance taps connect to switch ANT the arrangement being such as to short out portions of the inductance. A variable tuning slug is provided

to tune the antenna inductance. A capacitor C connects to one side of the inductive elements of the band switch and to ground. As mentioned above, the band switches B and B1 are both driven to the homing position X every time the panel knob 1 is operated. The arms of switches B and B1 are returned by the spring action of spring 98 to any of the four positions depending upon the preset height of the bushing of the adjustable cam 92. The band switches B and B1 are coupled to the selector mechanism by means of the coupling levers 120 and 122. The channel switches A and A1 are geared directly for rotation with the front panel knob 1 and is arranged to rotate one switch position for each 1.1° revolution of the front panel control. The switches A and A1 are coupled to the selector mechanism by means of the coupling levers 118 and 141, which levers are rotated by means of their respective rack and pinion gears. It will be noted that with this arrangement, it is possible to obtain ten different combinations of band and channel selections with a setting for any frequency within the range of the tuning equipment. Other combinations can be obtained by changing the number of switch positions for selecting the channels and bands in which the channels are found. Theoretically the channel switch and the band setting cam may have any number of settings or positions and the band switch and each plunger of the band setting cam may also have any number of settings or positions. Thus the total number of channels available for given apparatus can be expressed as $m \times n$ where m and n are any integers representing the number of positions to which the band switch and band setting plunger can be set and the number of positions of the channel switch and band setting cam, respectively. The total number of channels to which the apparatus can be preset is, of course, limited to n channels. While theoretically any finite number of channels and bands are possible, it will be recognized, of course, that practical limitations of the apparatus will reduce the number greatly. The device of this invention may be used to select switch positions for any type of electrical equipment other than that described above.

What I claim as my invention is:

1. A mechanism for positioning a complementary pair of adjustable positioning devices, including a single control member mechanically coupled to said one of said devices to position the same, a member mechanically coupled to said single control member and having a number of adjustable elements thereon for selection by operation of said single control member, and a further member engaging one of said elements selected by said single control member and mechanically coupled to said other of said devices to position the same in accordance with the position of the element selected by said single control member.
2. A mechanism for positioning a complementary pair of adjustable positioning devices, including a single control member mechanically coupled to said one of said devices to position the same, a member mechanically coupled to said single control member and having a number of adjustable elements thereon, a further member engaging one of said elements selected in response to actuation of said control member, said further member being mechanically coupled to said other of said devices selected by said single control member to position said other device, an addi-

tional member mechanically coupled to said single control member and said further member to urge said further member and said other of said devices to an initial position during actuation of said single control member, and an element mechanically coupled to said further member urging said further member and said other of said devices into position in accordance with the position of the element selected by said single control member.

3. A mechanism for positioning a complementary pair of adjustable positioning devices in n combinations of a total of $m \times n$ possible combinations, m and n being any integers, one of said devices being adjustable to n positions and the other to m positions, including a single control member mechanically coupled to said one of said devices to position the same, another member mechanically coupled to said single control member and having n elements each adjustable to m positions, and a further member engaging one of said elements selected in response to actuation of said single control member, said further member being mechanically coupled to said other of said devices to position the same in accordance with the position of said element selected by said single control member.

4. A mechanism for positioning a complementary pair of adjustable positioning devices in n combinations of a total of $m \times n$ possible combinations, m and n being any integers, one of said devices being adjustable to n positions and the other to m positions, including a single control member mechanically coupled to said one of said devices to position the same, another member mechanically coupled to said single control member and having n elements each adjustable to m positions, a further member engaging one of said elements as selected in response to actuation of said single control member, said further member being mechanically coupled to said other of said devices to position the same in accordance with the position of said element selected by said single control member, an additional member coupled to said single control member and said further member to urge said further member and said other of said devices to an initial position during actuation of said single control member, and an element mechanically coupled to said further member urging said further member and said other of said devices into position in accordance with the position of the element selected by said single control member.

5. A mechanism for positioning a complementary pair of adjustable positioning devices in n preset combinations of a total of $m \times n$ possible combinations, m and n being any integers, wherein one of said devices is adjustable to n positions and the other to m positions, including a single control member directly geared to said one of said devices to position the same, another member geared to said single control member and having n elements each adjustable to m positions, a further member engaging one of said elements as selected in accordance with actuation of said single control member, said further member being mechanically coupled to said other of said devices to position the same in accordance with the position of said element selected by said single control member, an additional member geared to said single control member and engaging said further member to urge said further member and said other of said devices to an initial position during actuation of said single control member, and an element mechanically

coupled to said further member urging said further member and said other of said devices into position in accordance with the position of the element selected by said single control member, and a pair of coacting members mechanically coupled to said other member and said single control member to arrest the control of said single control member at the extremities of travel of said other member.

10. A mechanism for selectively positioning a pair of complementary adjustable devices, including a single control element mechanically coupled to one of said devices to position the same in direct proportion to movement of said control element, a resilient member coupled to the other of said devices and urging the same in one direction of travel of said other device, an adjustable cam member mechanically coupled to said single control element and to said one device to be positioned in synchronism therewith, and a lever coupled to said other device and engaging said adjustable cam member, said lever and said adjustable cam member being arranged to limit travel of said one device in said one direction to effect the desired positioning of said other device corresponding to the positioning of said one device and said adjustable cam member.

7. A mechanism for selectively positioning a pair of complementary adjustable devices, including a single control element coupled to one of said devices to position the same in direct proportion to movement of said control element, a resilient member coupled to the other of said devices and urging the same in one direction of travel of said other device, an adjustable cam member mechanically coupled to said single control element and said one device to be positioned in synchronism therewith, a lever coupled to said other device and engaging said adjustable cam member, said lever and said adjustable cam member being arranged to limit travel of said one device in said one direction to effect the desired positioning of said other device corresponding to the positioning of said one device and said adjustable cam member, and a further member coupled to said control element and said lever to disengage the latter from said adjustable cam member during actuation of said control member.

8. A mechanism for positioning two complementary rotatable devices, including a single control shaft, a first shaft adapted to be coupled to one of said rotatable devices, gearing coupling said single control shaft and said first shaft, a mechanism arranged on said first shaft to rotate therewith and having a plurality of adjustable bushings arranged thereon, a bell crank having one arm thereof adapted to engage one of said bushings at a time, a rack coupled to the other arm of said bell crank, a pinion engaging said rack, a second shaft adapted to be coupled to another of said rotatably adjustable devices, a further gearing coupling said pinion and said second shaft, a cam geared to said single control shaft element, a cam follower affixed to said rack and engaging said cam to slide said rack and to rotate said bell crank to an inactive position during rotation of said control shaft, and a spring urging said bell crank into engagement with said bushings to govern travel of said bell crank and said rack in accordance with the height setting of the bushing selected by operation of said single control shaft.

9. A mechanism for positioning two complementary adjustable devices, including a single control element, a first member adapted to be coupled to one of said adjustable devices, gears

coupling said single control element and said first member, a drum arranged on said first member to rotate therewith, a plurality of adjustable bushings arranged around the periphery of said drum, each of said bushings having an internally located adjusting member arranged to vary the height of said bushing with respect to the circumferential surface of said drum, a lever arranged to be slidably moved, a cam geared to said single control element, a cam follower affixed to said lever and engaging said cam, a rack affixed to said lever parallel to the direction of sliding movement, a pinion engaging said rack, a second member adapted to be coupled to the other of said adjustable devices, a further gear coupling said pinion and said second member, said cam being arranged to slide said cam follower and said lever to an extreme position during movement of said control element, a bell crank having a shoe thereon coupled to said lever and arranged to engage one of said bushings as selected by actuation of said control element to restrain return of said lever in accordance with the height setting of the bushing selected by movement of said control element.

10. A mechanism for positioning complementary rotatable devices, including a single control shaft, a first shaft adapted to be coupled to one of said rotatable devices, a train of gears coupling said single control shaft and said first shaft, a drum arranged on said first shaft to rotate therewith, a plurality of adjustable bushings arranged around the periphery of said drum, each of said bushings having an internally located screw arranged to vary the height of said bushing with respect to the circumferential surface of said drum, an arm having a slot therein and arranged for reciprocating movement thereof, a cam geared to said single control shaft, a cam follower affixed to said arm and engaging said cam, a rack affixed to said arm, a pinion engaging said rack, a second shaft adapted to be coupled to the other of said rotatable devices, a further train of gears coupling said pinion and said second shaft, a spring urging said arm and said second shaft to an extreme position defined by the limits of said slot, said cam being arranged to move said arm to the opposite extreme position during rotation of said single control shaft, a bell crank coupled to said lever and having a shoe adapted to engage one of said bushings as selected by rotation of said single control shaft, a further spring urging said arm and said bell crank in contact with said bushing selected by rotation of said single control shaft to restrain the return of said arm in accordance with the height setting of the bushing.

11. A mechanism for positioning complementary rotatable devices, including a single control shaft, including a first shaft adapted to be coupled to one of said rotatable devices having a plurality of discrete active positions totalling less than 360° rotation, a train of gears coupling said single control shaft and said first shaft, a drum arranged on said first shaft to rotate therewith, a plurality of adjustable bushings arranged around the periphery of said drum in accordance with the spacing of the positions of said one rotatable device, each of said bushings having an internally arranged screw adapted to vary the height of said bushing with respect to the circumferential surface of said drum, an arm having a slot therein and arranged for reciprocating movement thereof limited by said slot, a cam geared to said single control shaft, a cam follower affixed to said arm and engaging said cam, a rack

affixed to said arm, a pinion engaging said rack, a second shaft adapted to be coupled to another of said rotatable devices, a further train of gears coupling said pinion and said second shaft, a spring urging said arm and said second shaft to an extreme position defined by the limits of said slot, said cam being arranged to move said arm to the opposite extreme position during rotation of said single control shaft, a bell crank coupled to said lever and having a shoe adapted to engage one of said bushings as selected by rotation of said single control shaft, a further spring urging said arm and said bell crank in contact with said bushing selected by rotation of said single control shaft to restrain the return of said arm in accordance with the height setting of the bushing, a further cam arranged to rotate with said drum, a further cam follower engaging said further cam and having a stop element thereon, a stop engaging member on said control shaft, said further cam having a configuration causing said stop element to engage said stop engaging member at either extremity of travel of said drum to prevent further rotation of said control shaft.

12. A mechanism for positioning an adjustable device to a plurality of predetermined positions within a prearranged sector of travel of said device, including a drive shaft, a mechanical coupling between said drive shaft and said adjustable device, a stop member arranged on said drive shaft, a cam mechanically coupled to said adjustable device, and a lever having a nose portion following said cam and a depending portion arranged selectively to engage said stop member, said cam having a configuration causing said lever to engage said stop member to prevent further rotation of said drive shaft in the forward direction at either end of said sector of travel.

13. A mechanism for positioning an adjustable device to a plurality of predetermined positions, within a prearranged sector of travel of said device, including a drive shaft, a mechanical coupling between said drive shaft and said adjustable device, said mechanical coupling having a ratio at which said drive shaft is rotated one full turn plus the interspacing between adjacent predetermined positions for each change of position of said adjustable device, a stop member arranged on said drive shaft, a cam mechanically coupled to said adjustable device, and a lever having a nose portion following said cam and a depending portion arranged selectively to engage said stop member, said cam having a configuration causing said lever to engage said stop member to prevent further rotation of said drive shaft in the forward direction at either end of said sector of travel.

14. A mechanism for positioning an adjustable device to a plurality of predetermined positions within a prearranged sector of travel of said device, including a drive shaft, a mechanical coupling between said drive shaft and said adjustable device, a stop member arranged on said drive shaft, a cam mechanically coupled to said adjustable device, and a lever having a nose portion following said cam and a depending portion arranged selectively to engage said stop member, said cam having a configuration causing said lever to engage said stop member to prevent further rotation of said drive shaft in the forward direction at either end of said sector of travel, a detent cam mechanically coupled to said drive shaft, the last said mechanical coupling having the same ratio as the first said mechanical coupling, and a spring loaded detent

follower riding said cam to indicate proper positioning of said drive shaft.

15. A mechanism for positioning an adjustable device to a plurality of predetermined positions, within a prearranged sector of travel of said device, including a drive shaft, a mechanical coupling between said drive shaft and said adjustable device, said mechanical coupling having a ratio at which said drive shaft is rotated one full turn plus the interspacing between adjacent predetermined positions for each change of position of said adjustable device, a stop member arranged on said drive shaft, a cam mechanically coupled to said adjustable device, and a lever having a nose portion following said cam and a depending portion arranged selectively to engage said stop member, said cam having a configuration causing said lever to engage said stop member to prevent further rotation of said drive shaft in the forward direction at either end of said sector of travel.

16. A mechanism for positioning an adjustable device to a plurality of prearranged positions within a predetermined positioning range, including a drive shaft, an adjustable cam, a mechanical coupling between said drive shaft and said adjustable cam, a cam following lever arranged selectively to engage said adjustable cam, a detent cam mechanically coupled to said drive shaft, a spring loaded detent follower riding said detent cam, a member having rack and lever portions slidably mounted on said detent follower, a pinion mechanically coupled to said adjustable device and engaging the rack portion of said member, the lever portion of said member being mechanically coupled to said cam following lever, said detent cam being operable in response to rotation of said drive shaft to shift said detent follower and said rack and lever member to disengage said cam following lever from said adjustable cam to enable rotation of the latter in response to further rotation of said drive shaft, and said cam following lever being operable to slide said rack and lever member on said detent follower to position said adjustable device in accordance with the setting of said adjustable cam.

17. A mechanism for positioning an adjustable device to a plurality of prearranged positions within a predetermined positioning range, including a drive shaft, an adjustable cam, a mechanical coupling between said drive shaft and said adjustable cam, a cam following lever arranged selectively to engage said adjustable cam, a detent cam mechanically coupled to said drive shaft, a spring loaded detent follower riding said detent cam, a member having rack and lever portions slidably mounted on said detent follower, a pinion mechanically coupled to said adjustable device and engaging the rack portion of said member, the lever portion of said member being mechanically coupled to said cam following lever, said detent cam being operable in response to rotation of said drive

shaft to shift said follower and said rack and lever member to disengage said cam following lever from said adjustable cam to enable rotation of the latter in response to further rotation of said drive shaft, said cam following lever being operable to slide said rack and lever member on said detent follower to position said adjustable device in accordance with the setting of said adjustable cam, a stop member arranged on said drive shaft, a cam mechanically coupled to said adjustable device, and a lever having a nose portion following said cam, and a depending portion arranged selectively to engage said stop member, said cam having a configuration causing said lever to engage said stop member to prevent further rotation of said drive shaft in the forward direction at either end of said sector of travel.

18. A mechanism for positioning an adjustable device to a plurality of prearranged positions within a predetermined positioning range, including a drive shaft, an adjustable cam, a mechanical coupling between said drive shaft and said adjustable cam, said mechanical coupling having a ratio at which said drive shaft is rotated one full turn plus the interspacing between adjacent predetermined positions for each change of position of said adjustable device, a cam following lever arranged selectively to engage said adjustable cam, a detent cam mechanically coupled to said drive shaft, a spring loaded detent follower riding said detent cam, a member having rack and lever portions slidably mounted on said detent follower, a pinion mechanically coupled to said adjustable device and engaging the rack portion of said member, the lever portion of said member being mechanically coupled to said cam following lever, said detent cam being operable in response to rotation of said drive shaft to shift said detent follower and said rack and lever member to disengage said cam following lever from said adjustable cam to enable rotation of the latter in response to further rotation of said drive shaft, said cam following lever being operable to slide said rack and lever member on said detent follower to position said adjustable device in accordance with the setting of said adjustable cam, a stop member arranged on said drive shaft, a cam mechanically coupled to said adjustable device, the last said mechanical coupling having the same ratio as the first said mechanical coupling, and a lever having nose position following said cam and a depending position arranged selectively to engage said stop member, said cam having a configuration causing said lever to engage said stop member to prevent further rotation of said drive shaft in the forward direction at either end of said sector of travel.
